Attorney

UNITED STATES PATENT OFFICE.

MARTIN J. PALMER, OF SEATTLE, WASHINGTON.

SAFETY-CLIP.

1,311,574.

Specification of Letters Patent. Patented July 29, 1919.

Application filed February 18, 1919. Serial No. 277,752.

To all whom it may concern:

Be it known that I, MARTIN J. PALMER, a citizen of the United States, and resident of the city of Seattle, county of King, and State 5 of Washington, have invented certain new and useful Improvements in Safety-Clips, of which the following is a specification.

My invention relates to clips or holders adapted for securement upon the edge of a 10 garment or fabric, as for instance the type of clip which is often used for the purpose of holding a pencil or penholder in a pocket.

The object of my invention is to provide a 15 clip or holder of this character which will grip the wall of the pocket or the edge of other fabric to which it may be applied, so as to prevent the possibility of its being pulled off unless its grip is loosened by some special action deliberately intended for that 20 purpose.

My invention comprises certain novel features of construction, whereby gripping points are provided which normally enter the fabric, so as to prevent removal and in 25 which the action of these gripping points may be neutralized at will.

The special features of my invention on 30 which I desire patent protection will first be described and then defined by the claims.

In the accompanying drawings, I have shown this device in the form of construction which I now prefer to employ.

Figure 1 is a side view of a pen or pencil showing my clip applied thereto.

Fig. 2 is a like view but showing the clip in face or front view.

Fig. 3 is a view in which the clip is shown in section along a central longitudinal plane.

Fig. 4 is an edge view of the device in a 40 slightly different form of construction.

Fig. 5 shows, in perspective, a portion of the device in the form of construction shown in Fig. 4.

My invention is adapted for use in connection with any mechanism which it may be desired to secure to the edge of a garment or fabric. I have illustrated it as being used in connection with a pen or a pencil clip, although it would be evident that the safety- 45 holding features of the invention are in a large measure independent of the article which is to be held. I will, however, describe

the same as used for the purpose indicated, it being understood that it may be employed for a wide variety of uses.

The base of the device consists of a bar or plate 1. This carries one or more points or pins, as 10, which project from the face thereof. These pins are herein shown as being formed by striking out a small portion 55 of the material of the bar 1.

Placed in position opposite the bar 1 is a bar 3, which forms one arm of the holding clip. Interposed between these two bars 1 and 3 is the releasing bar 2. This releasing 60 bar is provided with holes, as 20, so placed as to receive the pins or points 10. Normally the releasing bar 2 lies close beside the surface of the bar 1, as shown in Fig. 1. In this condition the points project enough to 65 securely engage with the side wall of a pocket, or the surface of a garment, or piece of fabric on which the clip is placed. In this condition, the device cannot be removed 70 by a straight pull, excepting by rupturing 75 the material of the fabric.

An arm 4, which as the device is illustrated, is an integral part of the outer bar 3, extends beyond the points of function of the various bars and forms a lever by which 80 the device may be released. By pressing this bar toward the pen or pencil which is held in the device, the releasing bar 2 is bowed outward, or away from the base bar 1 and therefore pushes the fabric off of the 85 holding pins 10. In this position of the parts, it is easy to remove the device from the fabric.

The free end of the releasing bar 2 should 90 be secured against outward movement relative to the base bar 1, as by means of a backwardly bent tip 11 of the said bar 1, which tip extends over the point of the base bar and prevents lateral displacement of the releasing bar, while at the same time permitting a slight longitudinal movement as may 95 be required by reason of the bending of this bar.

In the device as shown in Figs. 4 and 5, the end of the bar 2 is provided with a T-shaped head 21 and the backwardly bent tip 11 of the bar 1, is provided with short fingers 12 which engage at opposite sides of the bar 2 and prevent both lateral movement of

said bar and its removal from the socket formed by the tip 11 and the fingers 12.

If this device be grasped so as to press the arm 4 inward, it may be easily released from the pocket while a direct pull without pressing in the arm 4, will be resisted by the pin points 10.

What I claim as my invention is:

1. A safety clasp adapted to be secured upon a fabric edge comprising two opposed fingers adapted to pass at opposite sides of the fabric, one of said fingers having fabric engaging points and a spring-releasing finger fixed at one point and extending between said other fingers and having holes through which said points normally project.
2. A safety clasp adapted to be secured over the edge of a fabric, having two opposed fingers adapted to embrace the fabric edge, one finger having fabric engaging points projecting toward the other finger, a third finger fixed to and lying between the other two fingers and having holes through which said points may project, and means whereby that part of said third finger which incloses the fabric engaging points may be moved away from the finger having the points.
3. A safety clasp adapted to be secured over an edge of a pocket or garment, comprising three bars or fingers extending alongside each other and fixed together at one end, one of the outer bars having inwardly projecting fabric-engaging points and the central bar having openings through which said points may normally project, and means for separating said central bar and

the bar which carries the points to disengage the latter from the fabric.

4. A safety clasp for attachment to an edge of a pocket or garment comprising three fingers placed in superposed relationship and fixedly secured together at one end, one of the outer fingers having fabric engaging points in its middle portion and the central finger having holes through which said points normally project, the ends of said two fingers opposite those which are fixedly secured being held against lateral separation and to permit relative longitudinal movement, whereby the center finger may be bent to cover the points.

5. A safety clamp for attachment to a garment edge, comprising three fingers placed in superposed relation, the intermediate or central finger being secured by one end to one of the outer fingers, said outer finger being centrally provided with points and the central finger having holes through which said points normally project to engage the garment, the central finger having a section between said holes and the end which is fixedly secured to the outer finger, which section is offset from said outer finger, the third finger being secured to said offset section, and an arm extending from said offset section away from the points, whereby the central finger may be bent to clear the points from the garment.

Signed at Seattle, Washington, this 6th day of February, 1919.

MARTIN J. PALMER.
